ROTARY SNOW AND ICE BREAKER

Carmine Gangemi, Dover, N. J.

Application February 6, 1952, Serial No. 270,233

9 Claims. (Cl. 241—236)

1

This invention relates to snow and ice removing equipment, and in particular a snow and ice breaker for use in combination with snow melting machinery wherein snow and ice picked up by a loading machine is deposited in a hopper positioned above crushing rolls by which the snow and ice are crushed and deposited into an oven from which the products are drained off as water.

This invention includes an improvement in the snow and ice crushing elements of the snow melting machine of my copending application with Serial No. 57,084, now Patent No. 2,592,267, the crushing roller being replaced with a pair of rollers having caulk and spikes therein and these rolls in combination with a reel and stationary comb or saw tooth bar crush the snow and ice to comparatively fine particles which readily melt when subjected to heat.

The purpose of this invention is to improve the crushing elements of the machine of the co-pending application whereby the quantity of material handled by the melting machine is increased.

With the machine of the co-pending application and also in conventional machines of this type the operation of the machine is handicapped because blocks of ice melt comparatively slow and it has been found difficult to crush the ice sufficiently to permit continuous operation of the machine with the machine fed by a conventional loader. With this thought in mind this invention contemplates an improved method of crushing ice and snow whereby ice is crushed to such an extent that the machine will take and melt ice and snow as fast as it is fed to the machine.

The object of this invention is, therefore, to improve crushing elements of an ice and snow melting machine whereby the ice and snow are crushed to a convenient size for immediate melting.

Another object of the invention is to provide an ice and snow crushing unit that is adapted to be used in combination with a snow melting machine which is adapted to crush ice and snow as fast as they are fed to the machine by a conventional loader.

A further object of the invention is to provide an improved crushing unit for ice and snow melting machines in which the unit is of a simple and economical construction.

Crushing units for handling products picked up from a street, highway, or the like are subjected to abuse because rocks, bolts and other foreign matter may be deposited into the crushing elements with the snow and ice and for this reason it is essential that picks, caulk and other crushing elements be readily replaceable.

2

With these and other objects and advantages in view the invention embodies a pair of crushing rolls journaled in a housing below a feed hopper wherein ice and snow deposited into the hopper are carried downwardly between the crushing rolls and with picks and cogs on the surfaces of the rolls the ice and snow are crushed to comparatively small sizes. The crushing unit also includes a reel positioned above the rolls and a comb or saw tooth bar adjustably mounted below the rolls and positioned to coact with the cogs and picks for further crushing the ice.

Other features and advantages of the invention will appear from the following description taken in connection with the drawing, wherein:

Figure 1 is a longitudinal section through the intermediate part of a snow melting machine illustrating the crushing unit positioned on a oven of the machine.

Figure 2 is a sectional plan through the crushing unit showing the reel and crushing rollers and also the mounting elements therefor, said section being taken on line 2—2 of Fig. 1.

Figure 3 is a detail showing a side elevational view of one side of the crusher roll housing illustrating the driving chains for rotating the crushing rolls and reel.

Figure 4 is a detail on an enlarged scale showing a section similar to that shown in Fig. 1 illustrating the mounting of the cogs and picks and also showing the relative positions of the cogs and picks in relation to the saw tooth bar positioned below the crushing rolls.

Figure 5 is a view showing the outer surface of one of the crushing rolls with the said surface of the roll developed or flattened for the purpose of illustration.

Figure 6 is a detail showing a plan view of the saw tooth bar positioned below the crushing roll.

Figure 7 is a detail showing a side elevation of the saw tooth bar with one end of the bar broken away so that the parts thereof are shown in section.

Referring now to the drawings wherein like reference characters denote corresponding parts the improved ice and snow crushing unit of this invention includes crushing rolls 10 and 11 positioned in a housing, having end walls 12 and 13, side walls 14 and 15 and a cover 16, a reel 17 also positioned in the housing, a saw tooth bar 18 positioned below the crushing rolls and cogs 19 and picks 20 removably mounted in the crushing rolls and positioned to coact with the teeth of the bar 18, for crushing snow and ice passing between the surfaces of the rolls and the bar.

The crushing rolls 10 and 11 are mounted on

shafts 21 and 22 which are journaled, at one end, in bearings 23 and 24, respectively on a bar 25, and at the other end in bearings 26 and 27 on a bar 28.

The reel 17, which is formed of two spirally positioned strips of material is mounted on a shaft 29, one end of which is journaled in a bearing 30 extended upwardly from the bar 25 and the other end being journaled in a bearing 31 extended upwardly from the bar 28. The shafts 21 and 22 are provided with sprockets 32 and 33, respectively over which a chain 34 is trained and this chain extends over an idler sprocket 35 to suitable driving means for the unit. The shaft 22 is also provided with a sprocket 36 that drives the reel 17 through a sprocket 37 with a chain 38 that is trained over the sprockets 36 and 37.

The toothed bar 18 is formed as illustrated in Figs. 4, 6, and 7 with teeth 39 on one side and teeth 40 on the other and the bar, which is V-shaped in cross section is supported with end plates 41 and 42 with bolts 43 which extend through slots 44 and 45 in the plate 41 and slots 46 and 47 in the plate 42. The bolts secure the end plates to intermediate plates 48 and 49 which extend downwardly from the bars 25 and 28, respectively.

As illustrated in Fig. 4 the caulks 50, which are provided with threaded shanks 51 are threaded into openings 52 in the walls of the crushing rolls. The cogs are provided with flat sided flanges 53 by which they are gripped with a wrench or the like to facilitate insertion thereof in the openings and also the removal thereof from the openings. The caulks may, therefore, be readily removed and replaced.

The picks 54 are provided with tapering shanks 55 which extend through the similarly shaped openings 56 in the walls of the crushing rolls and, as shown in Fig. 4, the openings 56 extend from recesses 57 in the outer surfaces of the walls of the rolls to openings 58 which extend through the walls of the rolls. With the picks mounted in this manner they are driven into the tapering openings in which they are frictionally held for use and when it is desired to remove the picks a drift is driven into the opening 58 into which the end of the pick extends whereby the pick is dislodged from the opening 56.

The picks and caulks may, therefore, be readily removed and replaced and upon rotation of the crusher rolls the picks and caulks pass between the teeth of the bar 18, as illustrated in Fig. 4. The bar 18 is mounted with slotted openings at the ends whereby the position thereof in relation to the crushing rolls is adjustable.

Snow and ice are fed to the crusher rolls through a hopper 59 having an inclined wall 60 at one side and a baffle 61 at the other and, with the hopper positioned as shown in Fig. 1, the reel 17 extends upwardly into the lower end thereof.

The reel 17 not only provides means for distributing snow and ice over the surfaces of the rolls, but also provides means for initially breaking up cakes of snow and ice, the spirally disposed strips slicing through the masses of the snow and ice.

The end wall 62 of the housing is secured to the cover 63 with an angle 64 and channels 65 and 66 are provided at the lower ends of the end walls to facilitate mounting the crusher housing on an oven 67 of a snow melting truck 68. The oven 67 is provided with burner nozzles 68 and 69 at the upper end, a heating pipe

67 for heating the lower part of the oven and a drain connection 68. The intermediate part of the oven is provided with a vertically disposed baffle 69 and the baffle is positioned below an opening 70 through which the crushed snow and ice are supplied to the oven.

With the parts arranged in this manner snow and ice supplied with a conventional loader are deposited in the hopper 59 above the crushing rolls and with the rolls rotating the snow and ice are fed to the area between the rolls, and over the bar 18 whereby the products are crushed and only comparatively small particles thereof drop into the oven below the crusher unit.

By this means comparatively large quantities of snow and ice may be fed to the melting machine, and the snow and ice may be fed continuously with the machine reducing the product to water.

It will be understood that modification may be made in the design and arrangement of the parts without departing from the spirit of the invention.

What is claimed is:

1. Ice crushing units for ice and snow melting machines comprising a pair of crusher rolls, a reel including spaced spiral strips mounted above the rolls and positioned in a vertical plane extended between the rolls, a toothed bar having a V-shaped upper surface with notches in the edges also mounted in a vertical plane extended between the rolls and positioned below the rolls, and projections on the surfaces of the rolls positioned to register with the notches in the edges of the toothed bar to coact with the bar for crushing ice and snow passing downwardly between the crusher rolls.

2. In combination with an ice crushing unit as described in claim 1, a housing surrounding the rolls, reel and tooth bar, and means journaling the rolls and reel in the housing.

3. An ice crushing unit as described in claim 1 wherein the crusher rolls and reel are journaled in a housing and the housing is adapted to be positioned over an opening in an oven for melting snow, ice and the like.

4. An ice crushing unit as described in claim 1 wherein the projections on the surface of the rolls include caulks threaded into openings in the surfaces of the rolls.

5. An ice crushing unit as described in claim 1 wherein the projections on the surfaces of the rolls include picks having tapering shanks positioned in tapering openings in the surfaces of the rolls, the axes of said picks being tangent to circles extended through the intermediate parts of the walls of the rolls.

6. An ice crushing unit as described in claim 1 wherein projections on the surfaces of the rolls include cogs threaded into openings in the walls of the rolls and picks having tapering shanks positioned in tapering openings in the walls of the rolls, the axes of said picks being tangent to circles extended through intermediate parts of the walls of the rolls.

7. In an ice crushing unit for ice and snow melting machines, the combination which comprises a housing substantially rectangular shape in plan, crushing rolls positioned in said housing, parallel shafts journaled in the housing and upon which the rolls are mounted, a reel having spirally positioned elements positioned above the rolls, a toothed bar, V-shaped in cross section adjustably mounted in the housing and positioned below the rolls, said toothed bar and reel

being positioned in a vertical plane extended between the crusher rolls and a feed hopper in the upper end of the housing and positioned to feed ice and snow and the like to the rolls.

8. An ice crushing unit as described in claim 7, wherein the crusher rolls are provided with cogs threaded into the walls thereof from the outer surfaces and picks having tapering shanks in similarly shaped openings extended between recesses and openings in the walls of the rolls and wherein the spaces between the teeth of the toothed bar are positioned to receive the picks and cogs whereby the elements coact to crush ice and snow passing between the crusher rolls. 10

9. An ice crushing unit as described in claim 7 wherein the tooth bar is vertically adjustable to regulate the size of the crushed material traveling from the rolls. 15
